ADJUSTABLE BRUSH ASSEMBLY FOR
VACUUM CLEANERSCharles H. Sparklin and Frank S. Howard, Chi-
cago, Ill., assignors to Birtman Electric Com-
pany, a corporation of Illinois

Application April 20, 1946, Serial No. 663,710

6 Claims. (Cl. 15—183)

1

This invention relates to a brush assembly for a vacuum cleaner or the like.

Floor type vacuum cleaners employ a rotatable brush to loosen dirt and other foreign material from the surface being cleaned so that the air flow caused by the motor fan unit may pick this material up and draw it into a receiver. The bristles in the rotatable brush become worn in time and require either replacement or adjusting. When the bristles become very worn it is necessary that they be replaced. In many instances this requires replacing the entire brush. Various brush assemblies have been proposed where the brush element only need be replaced, but these have been undesirable in many cases, as it was not possible to adjust the brush element to the proper position, and it was oftentimes difficult to remove the worn brush element, and replace it with a new one.

In the present invention there is provided a rotatable brush body having a brush element held in the body with the brush element being adjustable to any given position. As the bristles become worn the element may be adjusted to compensate for this wear, and when a replacement is necessary the old brush element may be easily removed and a new one inserted.

The invention will be described as related to the embodiment shown in the accompanying drawings. Of the drawings Fig. 1 is a plan view of the new brush assembly; Fig. 2 is an elevation of the brush assembly with portions broken away for clarity of illustration; and Fig. 3 is a vertical section taken along line 3—3 of Fig. 2.

The brush assembly comprises an elongated hollow tube 10 of metal having caps 11 at each end thereof with projecting spindles 12 in the center of the caps 11 for mounting the brush assembly in the cleaner. There are provided elongated slots 13 on each end of the tube 10 with the slots being on diametrically opposed sides of the tube and each slot being substantially parallel to the longitudinal axis of the tube. The space between the adjacent ends of the slots serves as a hub that is adapted to be contacted by the driving belt or the like.

Each slot is arranged to hold an elongated rigid back member 14 having brush bristles 15 along its outer edge. As shown, this back member is made of wood and has a centrally located metal plate 16 on its inner edge attached to the back member by screws 17. The metal plate 16 has a threaded hole 18 therein designed to engage the threads on a threaded rod 19 which extends from the back member 14 through a hole

20 located opposite a slot 13. The threaded rod 19 is provided with a screw head 21 on its outer end, and is also provided with a tight-fitting washer 22 adjacent the inner surface of the tube 10. The threaded rod 19 serves to retain the back member 14 within the slot 13.

In order that the back member will be held firmly in place there are provided a pair of compression springs 23 adjacent each end of the back member 14. Each compression spring is held in a cavity 24 within the base member 14 and pushes against the inner surface of the tube 10. These springs are relatively strong, so that the back member will be held firmly in place.

15 The back member 14, and thus the bristles 15, may be easily adjusted relative to the tube 10 by inserting a screw driver or the like in a slot 25 in the screw head 21 and turning the threaded rod 19. This moves the back member 14 in and 20 out of the slot 13, depending upon the direction of rotation of the rod 19. The inner end of the rod 19 fits within a hole 26 within the back member 14.

When it is desired to replace the brushes the 25 rod 19 is unscrewed until it comes loose from the plate 16. The back member 14 may then be removed and replaced by a new one. The washer or collar 22 prevents losing the threaded rod. When the brush assembly is being rotated centrifugal force will tend to hold the back member 14 and bristles 15 in fully extended position. The compression springs 23 also serve to force the back member 14 outwardly against the restraint of the threaded rod 19.

35 Having described our invention as related to the embodiment set out in the accompanying drawings, it is our intention that the invention be not limited by the details of the description unless otherwise specified, but rather be construed broadly within its spirit and scope as set out in the accompanying claims.

We claim:

1. A rotatable brush assembly for a vacuum cleaner or the like comprising an elongated hollow tube, said tube having an elongated slot therein substantially parallel to the longitudinal axis of the tube, a brush element comprising a rigid back portion located in said slot and extending into the hollow interior of said tube, said brush having spaced bristles extending from said back portion, a threaded rod extending through an opening in the tube opposite the slot and engaging a threaded hole in the back portion at substantially the center thereof for securing the brush element in place, and compression springs

adjacent each end of the back portion with each spring being held in a cavity in the back portion and operating against the interior surface of the tube opposite the slot, said springs urging the brush element outwardly against the restraint of said rod but permitting each end of said brush element to be forced slightly inwardly of said tube when pressure is applied thereto.

2. A brush assembly for a vacuum cleaner or the like comprising an elongated hollow tube, said tube having an elongated slot therein substantially parallel to the longitudinal axis of the tube, a brush element comprising a rigid back portion located in said slot and extending into the hollow interior of said tube, said brush having spaced bristles extending from said back portion, a threaded rod extending through an opening in the tube opposite the slot and engaging a threaded hole in the back portion at substantially the center thereof for securing the brush element in place, and compression springs adjacent each end of the back portion with each spring being held in a cavity in the back portion and operating against the interior surface of the tube opposite the slot, said rod being provided at its outer end with a head contacting the outer surface of the tube and a collar around the rod and substantially rigid thereon adjacent the corresponding inner surface of the tube.

3. A rotatable brush assembly for a vacuum cleaner or the like comprising an elongated hollow tube, said tube having an elongated slot therein substantially parallel to the longitudinal axis of the tube, a brush element comprising a rigid back portion located in said slot extending into the hollow interior of said tube, said brush having spaced bristles extending from said back portion, a rotatable threaded rod engageable with said back portion and the tube at a point opposite the back portion for securing the brush element within the slot with said threaded rod engaging a threaded hole in said back portion, and spring means operating against the back portion of the brush element tending to force the brush element out through the slot, said spring means comprising a pair of springs with each spring adjacent an end of said rigid back portion and with said threaded rod engaging said back portion at substantially the center thereof, said springs urging the brush element outwardly against the restraint of said rod but permitting each end of said brush element to be forced slightly inwardly of said tube when pressure is applied thereto.

4. The brush assembly of claim 3 wherein the

springs are substantially equidistant from their adjacent ends of said rigid back portion.

5. A rotatable brush assembly for a vacuum cleaner or the like comprising an elongated hollow body having a longitudinal opening therein, a brush element including a substantially rigid back portion located in said opening and movable outwardly and inwardly in said opening to adjust the position of the brush, said brush element being supported against lateral displacement by the edges of the hollow body defining said opening, rotatable means located within said hollow body and adjustably connected to said back portion at a point intermediate the ends thereof for adjusting the position of said brush element outwardly and inwardly of said opening on rotation of said rotatable means, said rotatable means having an operating part located on and contacting the exterior surface of said body on the side opposite said opening for rotating said rotatable means and thus adjusting the position of the brush element outwardly and inwardly of said opening, and yielding means within said hollow body bearing against said back portion and urging the brush element outwardly against the restraint of said rotatable means.

6. The brush assembly of claim 5 wherein said hollow body is substantially cylindrical and said rotatable means comprises a bolt extending substantially diametrically of said body and engaging said brush back portion at substantially the center thereof.
